VENDING MACHINE FOR HOT BEVERAGES OR THE LIKE

Joseph E. Pierce and William C. Christine, Allentown,
Pa., assignors to Allen Electronics, Inc., Allentown,
Pa., a corporation of Pennsylvania

Filed Jan. 23, 1962, Ser. No. 68,491

Term of patent 14 years

The undisclosed side of the vending machine is substantially the same in appearance as the side shown, and the rear is plain.

The dominant features of our new design are shown in full lines.

We claim:

The ornamental design for a vending machine for hot beverages or the like, as shown and described.
